ERNEST OLDENBUSCH, OF BROOKLYN, NEW YORK

HOLDER FOR GRAPHIC INSTRUMENTS

Application filed August 2, 1928. Serial No. 297,049.

This invention relates to a holder for a graphic instrument, and has especial reference to a fountain pen desk holder adapted to hold a fountain pen or other closely analogous instrument conveniently disposed in an angular position.

The principal object of the invention is the provision of a holder of the indicated character embodying improvements in construction whereby the holder will accommodate and yieldingly or tensionally hold pens of different sizes.

The invention also resides in details of construction hereinafter described and illustrated in the accompanying drawing, in which

Figure 1 is a sectional view of the holder constructed in accordance with the invention;

Figure 2 is an elevation of the inner tubular member showing the springs associated therewith;

Figure 3 shows one end of the outer tubular member of the pen receptacle in elevation;

Figure 4 is a perspective view of the inner tubular member of the pen receptacle;

Figure 5 is a perspective view of one of the pen gripping springs.

In the illustrated embodiment of the invention, there is shown a base 10, ball and socket joint 11 connected with the base 10, and a pen receptacle 12 connected with the ball and socket joint 11.

The pen receptacle 12 which embodies the novel features of the invention includes an outer tapering tubular member 13, preferably of metal and of the proper size and length. The receptacle 12 also includes an inner tapering tubular member 14 somewhat shorter in length than the tubular member 13 and adapted to fit within the same. The tubular member 14 is provided with a plurality of notches 15 in each end thereof, there being four notches in the present instance. Springs 16 are employed, there being four to correspond to the number of notches 15 in each end of the tubular member 14. Each spring 16 is produced from a single piece of spring steel bent and formed to provide an

angularly disposed end 17 having shoulders 18, and an end 19 normally disposed at an angle with respect to the intermediate portions 20. The springs 16 are associated with the tubular member 14, by engaging the opposite ends of each of the springs in a pair of the notches 15 respectively in the opposite ends of the tubular member 14. The springs 16 are temporarily held in place by the use of a cone shaped cap 21 fitted over the small or inner end of the tubular member 14, as shown most clearly in Figure 2. It will be apparent that the shoulders 18 of each spring 16 will prevent lateral swinging movement of the spring relatively to the tubular member 14 by contact with the cap 21. The cap 21 has a central hole 22. The tubular member 14 with the springs 16 in association therewith is inserted in the tubular member 13. This assemblage is then brought down over a suitable mandrel to flex the springs 16 against the wall of the tubular member 14, and in the same operation a collar 23 is secured in place on the outer ends of the tubular members 13 and 14 to engage and confine the ends 19 of the springs 16 against displacement, as shown most clearly in Figure 1. It will also be apparent that the ends 19 of the springs 16 will be disposed between the tubular members 13 and 14 while engaged in the notches 15 in the inner end of the tubular member 14 to thus hold the intermediate portions 20 of the springs in bowed condition. The tubular member 13 has fitted thereon a cap 24 which accommodates a suitable fastening element, such as a screw 25 screwed into the ball of the joint 11.

From the foregoing, it will be apparent that a receptacle constructed in the manner set forth will accommodate and yieldingly or tensionally hold fountain pens of different sizes, the said springs 16 serving to tensionally grip the tapered end of the pen when inserted in the receptacle. It will also be observed that the hole 22 in the cap will allow the nib of the pen to project through the cap without in any way being impaired. It will also be apparent that the ends 19 of the spring will be disposed radially at an angle to the

longitudinal axis of the receptacle 12 and so facilitate the insertion of the pen.

What is claimed is:

1. A pen holder including a pen holding means consisting of tubular members, springs, and a collar, the springs being held in place by said tubular members and collar, the inner ends of the springs being engaged between the tubular members and the outer ends of the springs being engaged by the tubular members and collar, said springs serving to engage the barrel of a pen and tensionally hold it in position.
2. A pen holder including a pen holding means consisting of inner and outer tapering tubular members, the inner tubular member having notches in each end, springs arranged on the inside of the inner tubular member with the opposite ends of the springs disposed in said notches, one end of each spring projecting between the tubular members in contact therewith, and a collar fitting over the outer ends of the tubular members and provided with an inturned flange in engagement with the outer end of each spring.
3. A pen receiving and holding device including a tubular member, springs associated with said tubular member, a receptacle adapted to fit around the tubular member and an inturned flange carried at the end of the receptacle engageable with the outer ends of the springs and the outer end of the tubular member, the inner ends of said springs being re-bent and engaged between said tubular member and receptacle, said springs thus being held in place to tensionally engage the barrel of a pen to hold the pen in position.
4. A pen receiving and holding device including a tapering tubular member, elongated springs each having the opposite ends thereof in engagement with the opposite end portions of said tubular member, a second longer tubular member adapted to fit over said tubular member first mentioned, and a collar fitting over the outer ends of the tubular members and the outer ends of the springs, the inner ends of said springs being engaged between said tubular members, the springs thus held being of bowed form and serving to tensionally engage the barrel of a pen to hold the pen in position.

Signed at Brooklyn, in the county of Kings and State of New York, this 1st day of

55 August, A. D. 1928.

ERNEST OLDENBUSCH.
